UNITED STATES PATENT OFFICE.

AXEL HOLMSTRÖM, OF VILLA AEROVIK, VIGGBYHOLM, SWEDEN.

PADDLE-SHAFT MOUNTING FOR ETCHING MACHINES.

Application filed August 20, 1923. Serial No. 653,478.

To all whom it may concern:

Be it known that I, AXEL HOLMSTRÖM, a subject of the King of Sweden, residing at Villa Aerovik, Viggbyholm, Sweden, have

5 invented a certain new and useful Paddle-Shaft Mounting for Etching Machines, of which the following is a specification.

10 My invention relates to etching machines and more particularly to etching machines in which the acid is sprayed upon the plates to be etched by means of a revolving paddle, and to the mounting of the paddles.

15 The main purpose of my invention is to provide inexpensive means for easy insertion and the replacement of the paddle, as well as for easy adjustment in the relative positions of the paddle sections.

20 A further purpose is to prevent the sprayed liquor from getting without the box at the shaft opening, shaping sleeves extending through the openings so as to utilize centrifugal force upon any liquor falling upon the sleeves to return the liquor to the box.

25 A further purpose is to radially flare the sleeves as they extend inwardly in order to make liquor falling upon them travel inwardly.

30 A further purpose is to radially flange the sleeves at their inner ends so as to make liquor reaching their outer ends flow radially outward.

35 Further purposes will appear in the specification and in the claims.

40 I have preferred to illustrate my invention by a few forms only of the many in which it may appear, selecting these because they well illustrate the principles involved, while at the same time they are inexpensive and efficient.

45 Figure 1 is a sectional diagrammatical view to illustrate the position and duty of a paddle used in etching.

Figure 2 is a side elevation of an etching box equipped with my invention.

Figure 3 is a broken section upon the line 3—3 of Figure 2.

Figure 4 is broken enlarged detail from Figure 3.

50 Figures 5 and 6 show in broken section modified forms of a detail.

Figures 7 to 11 are broken sectional elevations indicating modifications of details.

In all drawings like numbers refer to like parts.

55 Referring to the drawings and describing in illustration and not in limitation:—

In etching devices of this character the acid is conveniently placed within a stoneware or earthenware box and is thrown 60 upon the plates by means of a stoneware or earthenware paddle or paddles mounted upon a shaft that is protected from the acid by the hubs of the paddles and a protective coating of rubber. The bearings of the 65 shaft are placed outside of the box to be away from the acid, the shaft extending clear through the box and having a bearing at each end.

70 The etching process is well illustrated diagrammatically in Figure 1. The level of the etching liquor is well below the shaft. A revolving blade upon the paddle dips into the liquor, picks up the liquor and casts it against a baffle in such a way as to spray 75 it upon the plates placed along an opposite wall of the box.

75 The stoneware tank 14 is filled with etching liquor to a level a — a considerably below the shaft 15 which carries the stoneware 80 paddle 16. The shaft 15 extends through the sides of the box to suitable bearings 17, as seen in Figures 2 and 3. The revolving paddles cast the etching liquor into the baffle space 18 and past the baffle 19 against 85 plates 20 set upon a groove 21 along the stoneware rest plate 22. The box has a removable cover 23 and a glass cover portion 24 usually left in place. A fan 25 draws a continuous stream of air into the box 90 through an opening 26 and spaces 27 and 28 at the ends of the shaft and carries off the fumes with the air to a suitable chimney not shown.

95 When etching a plate the cover is first removed, if it be on, the plate 20 is set upon the groove 21, the cover 23 is replaced, the paddle is started and kept running for a suitable time drenching the plate with etching liquor; the paddle is then stopped, 100 the cover removed and the plate taken out and washed free from etching liquor.

The shaft at each end turns within a universal joint bearing 17. The shaft turns directly in a box 33 which is pivoted horizontally at 34 and vertically at 35, the box 33 being free to turn vertically on the pivot 34 and the pivot 34 being free to turn horizontally on the pivot 35.

The paddle 16 is preferably made in a number of sections (four shown in Figure 10 3, at 29, 30, 31, 32) so that if there should be breakage, as by reason of an operator dropping a plate upon a paddle section, a short section only will have to be replaced. This arrangement too permits staggering the 15 blades of the different sections thereby giving more uniform torque and spray.

Hitherto it has been usual to assemble the paddle sections loosely upon the shaft through the top of the box and then while 20 in the box to seal them to the shaft by flowing between the shaft and the paddle hubs a molten compound, such as pitch, which hardens on cooling and maintains the paddle sections rigid with the shaft.

25 When a paddle section has broken it has been necessary to carefully heat the paddle sections while in the box to melt the compound sealing them to the shaft so as to be able to slide out the sections to the broken one by sliding out the shaft; a new section and the unbroken old sections to be put back in the same way. It has required both time and skill to do this properly and frequently unbroken sections have broken in heating, 30 burst by the swelling compound or cracked by unequal expansion.

35 My invention is directed toward simultaneously lessening the cost and time and skill needed for the replacement of broken sections, and also in providing an arrangement whereby the centering of the paddle sections with respect to the shaft becomes automatic and angular adjustment in the 40 positions of the blades very easy, while at the same time the side openings and the shaft are effectively sealed from the etching liquor and from the fumes thereof.

The bearings 17 are supported by brackets 36 upon the cross bars 37 clamped to place 50 against rubber washers 38 upon the outside of the box by tie rods 39.

The central portion of the shaft is preferably provided with protective enamel 40 which may be of asphaltum or other acid-resistant paint.

55 The soft resilient sleeves 41 between the shaft and the hubs 42 are provided with radial flanges 43 across the ends of the hubs to form resilient gaskets between the paddle 60 sections. The sleeves 44, at the sides of the box, are of stoneware or other acid-resistant material. They extend through the box and are pressed inward between washers 45 and 65 nuts 47 and 48 threaded upon the shaft. Their inner faces press against the

gaskets 43 of the adjacent paddle sections, thereby sealing the shaft from acid of the box. These sleeves are so shaped that centrifugal force guides the spray falling upon them toward the interior of the box.

70 The washers 45 and 46 are preferably sufficiently soft to seal the shaft at the outer end of the sleeves against any seepage of etching liquor from along the outside of the sleeves, and to provide easy connection 75 between the sleeve and nut. I have found aluminum a suitable material for these washers and that the quantity of liquor that may get to these washers is usually very small. Where these washers are harder than 80 aluminum or where conditions are such that there is likelihood of more than a minute quantity of liquor reaching them additional gasket washers of acid-resistant material may be inserted between the washers and 85 the sleeves, as in Figure 7.

The sleeves at the sides of the box are preferably tapered, flaring as they extend inward so that any liquor reaching the sleeve will tend to flow inward by reason of centrifugal force. The openings through the box walls for the sleeves taper to correspond to the taper of the sleeves. Drain grooves 49 and 50, respectively upon the exterior of the sleeve and the interior of the opening in 90 the box wall are provided to catch liquor that may tend to run along the sleeve after the paddle has stopped revolving, and the groove or grooves 49 of the sleeve are placed further in along the shaft than the grooves 95 50 so that any liquor cast from these grooves when the paddle starts that may strike the top of the opening through the box and tend to run outwardly will be caught in the groove 50.

100 In Figures 3, 4 and 8 the box walls are provided with an inward boss 51 around each tapered opening and this boss is radially flanged at 52 around its inner end so that any liquor falling upon the boss will 110 flow around the outside of the boss to fall off at the bottom without an opportunity to get into the opening.

115 In Figure 8 the taper of the sleeve extends to the inner end of the sleeve and during rotation of the paddle liquor falling upon the sleeve between the boss and paddle flows up centrifugally to the paddle and thence out centrifugally to be sprayed from the blades, and when the paddle stops, substantially all 120 that may tend to flow outwardly along the top of the sleeve or the top of the opening will be caught in one or other of the grooves and returned to the box. The bottom of the boss is slotted at 53 for the return to the 125 box of any liquor reaching the bottom of the opening.

130 In Figures 3 and 4 the sleeve at its inner end is radially flanged at 54 and inclined diagonally backward and outward at 55 to

cover the clearance space 56 between the inner edge of the boss and the flange 54, preferably extending beyond the raised rim 52 of the boss. The end of this diagonal flange 55 is covered by the conical flange portion 57 of the box, conically inclined toward the shaft. The conical flange 57 performs the double function of shielding the flange 55 from any hard object accidentally dropped from above and of shielding the space 58 around the boss 51 from any violent slushes of etching liquor when starting or stopping the paddle. The flange 57 is left open at the bottom at 59 for drainage back to the box.

15 It is obvious that the different elements of the arrangement for preventing the liquor from getting out the opening for the shaft have independent value as well as their value in the combinations shown and claimed 20 and they may be varied considerably without departing from the invention. This is well illustrated by the forms shown in Figures 7 to 11.

25 In Figure 7 the inward boss 51' and the sleeve 44' are made straight instead of taper and the outer hood 57 and grooves 49 and 50 of Figure 4 are dispensed with.

30 In Figure 9 the reversely inclined flange terminal (55 of Figures 4 and 7) of the sleeve is dispensed with, the grooves however being shown.

35 In Figures 10 and 11 the boss around the sleeve is outside instead of inside the box. In Figure 10 the box is recessed or dished around the radial flange of the sleeve, a lip 57 (analogous to the hood 57 of Figure 4) protecting the flange from slushes of liquor and from objects above. In Figure 11 the radial flange is left uncovered.

40 The soft resilient flanged sleeves 41, 43, are preferably of T-sections as seen in Figures 3, 4 and 7-11. One of these sections is inserted in each end of each paddle section, making paddle section units having 45 ends faced by the flanges 43 and bushed by the sleeves 41 fitting the shaft. In this arrangement the bushing-flange sections and the sections for the paddles are all alike and interchangeable. In Figures 5 and 6 are 50 shown modified forms of these bushing-flange sections. In Figure 5 it is made of a + section, to simultaneously fit two of the paddle sections. This form however is considered less desirable than the interchangeable form of Figure 4, and with it the individual paddle sections are somewhat less easy to put on or off.

55 The form of Figure 6 is like that of Figure 4 except that the sleeve is conical instead of cylindrical, to fit a corresponding conical bore of the paddle section.

60 When replacing a section one of the nuts 47 or 48 is taken off and the shaft is slid out longitudinally, with or without first starting the rubber sleeves to slide on the

shaft by slightly tightening the other nut; the paddle section units are lifted out from the top of the box one at a time until the broken unit has been taken out. The new unit and unbroken old units are then put 70 back in the same way, from the top of the box, and finally are clamped between the nuts.

75 It will be obvious too that the openings for the shaft in opposite sides of the box 75 are so sealed as to prevent either the etching liquor or its fumes escaping at these holes.

80 And further it will be obvious, that the shaft is well protected and sealed from the etching liquor and the fumes thereof, irrespective of the protective coating 40 shown in Figure 4.

85 In view of my invention and disclosure modifications and variations, to meet individual whim or particular need, will 35 doubtless become evident to others skilled in the art, and I claim all such in so far as they fall within the reasonable spirit and scope of my invention.

90 Having thus described my invention, what I claim as new and desire to secure by Letters Patent is:—

1. In a paddle wheel assemblage for an etching machine, the combination of a plurality of paddle sections, a driving shaft 95 adapted to pass through the sections, a sleeve upon each end of the driving shaft, clamping means for moving the sleeves relatively toward each other and cushions between the paddle wheel sections axially and 100 between the sections and the shaft radially for supporting and sealing the sections and for damping vibration in the sections.

2. In an etching machine, a box internally 105 resistant to etching liquor and having an opening, a shaft normally passing through the opening, a paddle resistant to etching liquor and having a hub of larger bore than and surrounding the shaft, and a soft rubber sleeve connection between the shaft and 110 hub.

3. In an etching machine, a paddle section unit having a hub bushed and faced with rubber, a shaft upon which the hub is removably and resiliently mounted and 115 means surrounding the shaft and resistant to etching liquor removably clamping the faces of the hub.

4. In an etching machine, a paddle section having a hub, a flanged bushing of resilient material bushing and facing each end of the hub, a shaft through the hub and connected thereto by the bushings and means surrounding the shaft and resistant to etching liquor removably clamping the faces of the hub.

5. In an etching machine, a paddle section having a hub, a flanged bushing of resilient and acid-resistant material bushing and facing each end of the hub, a shaft

through the hub and connected thereto by the bushings and means surrounding the shaft and resistant to etching liquor removably clamping the faces of the hub.

5. In an etching machine, a paddle section having a hub, an L-section flanged bushing of resilient material removably bushing and facing each end of the hub, a shaft through the hub and connected thereto by the bushings, and means surrounding the shaft and resistant to etching liquor removably clamping the faces of the hub.

6. In an etching machine, a box internally resistant to etching liquor and having an opening, a shaft normally passing through the opening, a pair of paddle sections resistant to etching liquor and having hubs of larger bore than the shaft, removable means for connecting and relatively centering the paddle sections and the shaft, a gasket between the hubs and surrounding the shaft, and other removable means surrounding the shaft and clamping the hubs together against the gasket.

7. In an etching machine, a box internally resistant to etching liquor and having opposite lateral openings, a shaft passing through the openings, threads upon the shaft, a plurality of resilient paddle section supports upon the shaft, paddle sections upon the supports, spaced thereby from the shaft and from each other and clamping means including nuts mounted upon the shaft threads for holding the shaft sections together axially of the shaft.

8. In an etching machine, a box internally resistant to etching liquor and having opposite lateral openings, a shaft normally passing through both openings, a plurality of liquor resistant paddle sections within the box resiliently and removably mounted along the shaft, gaskets therebetween, a liquor-resistant sleeve at and through each opening upon the shaft, a gasket between each sleeve and its adjacent paddle section, and nuts threaded upon the shaft, one at the outer end of each sleeve adapted together to adjustably inwardly position and to clamp the different sections into the gaskets.

9. In an etching machine, a box internally resistant to etching liquor and having a lateral opening, a shaft normally passing through the opening, a paddle section resistant to etching liquor within the box and mounted upon the shaft and a liquor-resistant sleeve mounted upon the shaft through the opening to seal against the paddle section and tapering so as to radially flare as it extends inwardly.

10. In an etching machine, a box internally resistant to etching liquor and having a lateral opening which slopes downwardly and inwardly at the bottom so as to drain

into the box interior, a shaft normally passing through the opening, a paddle section resistant to etching liquor within the box and mounted upon the shaft, and an etching-liquor-resistant removable tapered sleeve mounted upon the shaft through the opening, the larger end being inward and having at its inner end a radial flange sealing with the paddle section.

11. In an etching machine, a box internally resistant to etching liquor having a lateral opening draining into the box interior and a circumferential groove about the interior of the opening communicating with the drain, a shaft normally passing through the opening, a paddle section resistant to etching liquor within the box and mounted upon the shaft, and a liquor-resistant removable sleeve mounted upon the shaft through the opening, sealing with the paddle section and having at its inner end a radial flange sealing with the paddle section.

12. In an etching machine, a box internally resistant to etching liquor having a lateral opening draining into the box interior and a circumferential groove about the interior of the opening communicating with the drain, a shaft normally passing through the opening, a paddle section resistant to etching liquor within the box and mounted upon the shaft, and a liquor-resistant removable sleeve mounted upon the shaft through the opening, sealing with the paddle section and having within the opening an external circumferential groove for drainage.

13. In an etching machine, a box internally resistant to etching liquor having a lateral opening draining into the box interior and a circumferential groove about the interior of the opening communicating with the drain, a shaft normally passing through the opening, a paddle section resistant to etching liquor within the box and mounted upon the shaft, and a liquor-resistant removable sleeve mounted upon the shaft through the opening, sealing with the paddle section and having inwardly from the groove of the opening but within the opening an external circumferential groove for drainage.

14. In an etching machine, a box internally resistant to etching liquor having a lateral opening, an inwardly extending boss on the box around the opening radially flanging at its inner end to form a drainage groove around the outside of the boss, a shaft normally passing through the opening, a paddle section resistant to etching liquor within the box and mounted upon the shaft, and a liquor-resistant removable sleeve mounted upon the shaft through the opening, radially flanging at its inner end in sealing with the paddle section and thence diagonally flanging backward and outward to hood the inner edge of the boss.

15. In an etching machine, a box internally resistant to etching liquor having a lateral opening, an inwardly extending boss on the box around the opening radially flanging at its inner end to form a drainage groove around the outside of the boss, a shaft normally passing through the opening, a paddle section resistant to etching liquor within the box and mounted upon the shaft, and a liquor-resistant removable sleeve mounted upon the shaft through the opening, radially flanging at its inner end in sealing with the paddle section and thence diagonally flanging backward and outward to hood the inner edge of the boss.

diagonally flanging backward and outward to hood the inner edge of the boss, and an outer hood conically flanging from the wall of the box toward the shaft around the out-
5 side of the backward flange of the sleeve and having a drain opening at its lower side.

16. In an etching machine, a box internally resistant to etching liquor and having a lateral opening internally flaring inward
10 and draining to the box, a paddle section resistant to etching liquor within the box and mounted on the shaft, a liquor-resistant sleeve mounted upon the shaft through the opening, radially flaring as it extends in-
15 ward and radially flanging at its inner end in sealing against the paddle section, and an inwardly extending boss on the wall of the box around the opening and radially flanging at its inner end.

20 17. In an etching machine, a box internally resistant to etching liquor and having a lateral opening internally flaring inward and draining inward, an inwardly ex-
tending boss around the opening on the box

25 flanged outward at its inner end, a paddle section resistant to etching liquor mounted upon the shaft within the box, a liquor resistant sleeve mounted removably upon the shaft through the opening, radially flar-
30 ging as it extends inward, radially flanging at its inner end in sealing against the paddle section and thence diagonally flanging backwardly and outwardly to hood the inner rim of the boss, and an outer hood conically flanging from the wall of the box in-
35 wardly toward the shaft around the out-
side of the backwardly extending flange of the sleeve and having a drain opening at its lower side.

40 18. In an etching machine, a box internally resistant to etching liquor and having a lateral opening internally flaring and hooded at its inner end, a paddle section resistant to etching liquor mounted upon the shaft within the box, and a liquor-
45 resistant sleeve radially flaring within the hood and sealing with the paddle section.

19. In a paddle wheel unit, a paddle wheel shaft, a sleeve upon each end of the shaft, a nut upon the shaft at one end and a stop 50 at the other adapted to clamp the sleeves relatively, and a plurality of interspersed paddle wheel sections and gaskets main-
tained in sealing engagement axially of the shaft by pressure from the nut. 55

20. In an etching machine, a box internally resistant to etching liquor and having lateral openings, a stationary inwardly ex-
tending boss continuing one of the open-
ings, a paddle wheel within the box, a shaft 60 for the paddle wheel extending through the openings, a sleeve surrounding the shaft and extending outwardly from the inside into one of the openings and an inner flange upon the sleeve of larger diameter than the 65 sleeve and having the outer end of the flange extending toward the outside of the box to overhang the end of the sleeve.

21. In an etching machine, a box internally resistant to etching liquor and having 70 lateral openings, a stationary inwardly ex-
tending boss continuing one of the openings, a paddle wheel within the box, a shaft for the paddle wheel extending through the openings, a sleeve surrounding the shaft and 75 extending outwardly from the inside into one of the openings, an inner flange upon the sleeve of larger diameter than the sleeve and having the outer end of the flange ex-
tending toward the outside of the box to 80 overhang the end of the sleeve and a station-
ary hood overhanging the outer end of the flange.

22. In an etching machine, a paddle as-
semblage, comprising a plurality of hollow 85 paddle sections, a shaft smaller in diameter than the hollow of the sections, sleeves one at each end mounted upon the shaft, re-
silient gaskets for the paddle wheel sections adapted to support the sections from the 90 shaft and to seal and cushion the sections and means upon the shaft for forcing the sleeves and paddle wheel sections together.

AXEL HOLMSTRÖM.
